UNITED STATES PATENT OFFICE.

MARSHALL B. LLOYD, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

MACHINE FOR WEAVING REED FABRIC.

Application filed December 29, 1924. Serial No. 758,548.

My invention relates generally to improvements in machines for weaving reed fabric, which comprises a plurality of spaced members called "stakes" upon which long strands 5 called "fillers" are woven, over some of the stakes and under others.

The primary object of the invention is to produce a reed weaving machine capable of automatically producing in the finished fabric, a design or ornamentation by arranging or weaving the filler strand at predetermined intervals in a plurality of courses over and under predetermined stakes, thus presenting a contrast of appearance to produce the design 10 or ornamentation thereof, relative to the single course of over and under weaving of the filler strand upon the stakes and which comprises the main body of the finished fabric.

Another object of the invention is to so construct the machine that the weaving of the designs in a fabric is automatically controlled by a tape of peculiar construction which actuates the stake staggering means to hold the 15 desired stakes in a manner permitting the laying of the strand with respect thereto, thus producing the design or ornamentation therein, the designs, of course, varying in accordance with the particular tape or ribbon to be used.

A further object of the invention is to produce a machine wherein the designs or ornamentations are uniform and may be produced upon opposite sides of the finished fabric so 20 that when the same is applied to an article, as for instance a baby carriage, a design appears in symmetrical arrangement and proportions upon each side of the baby carriage.

My invention further consists in the form, 25 construction, and arrangement, and co-operation of the various parts thereof, whereby the above mentioned objects, together with other objects and advantages which will hereinafter appear, are readily attainable and my invention 30 will be more readily understood by reference to the accompanying drawings which illustrate that form of my invention which I consider at this time the preferred form.

In said drawings:

Fig. 1 is a perspective view of the upper-

most part of a weaving machine embodying my invention.

Fig. 2 is a vertical sectional view through a weaving machine embodying my invention, only a few of the many similar parts thereof being shown for the sake of clearness of illustration.

Fig. 3 is a horizontal sectional view through the same on an enlarged scale, as taken on the line 3—3 of Fig. 2.

Fig. 4 is a perspective view of one of the ribbon guide plate holding members embodied in my improved weaving machine and which will be more fully referred to later.

Fig. 5 is an enlarged detail vertical sectional view as taken on the line 5—5 of Fig. 3.

Fig. 6 is a perspective view of the coating parts forming the top of one of the ribbon guides.

Fig. 7 is a perspective view of the coating plates forming the bottom of one of said ribbon guides.

Fig. 8 is a detail view in elevation on an enlarged scale of the parts shown at the bottom of Fig. 1 and which will be more fully referred to later.

Fig. 9 is a horizontal detail sectional view as taken on the line 9—9 of Fig. 8.

Fig. 10 is a fragmentary vertical detail sectional view as taken on the line 10—10 of Fig. 3.

Fig. 11 is a top plan view of the ribbon or tape reels and associated parts and which will be more fully referred to later.

Fig. 12 is a fragmentary longitudinal detail sectional view as taken on the line 12—12 of Fig. 11.

Fig. 13 is a fragmentary vertical detail sectional view as taken on the line 13—13 of Fig. 3.

Figs. 14 and 15 are detail horizontal sectional views as taken on the lines 14—14 and 15—15 respectively of Fig. 13.

Fig. 16 is a transverse vertical sectional view as taken on the line 16—16 of Fig. 11.

The improved machine as herein illustrated and described is similar in some respects to the machine forming the subject-matter of my prior Patent No. 1,459,781 issued on June 26, 1923. The embodiment of

the present invention shown herein comprises generally the following parts:

Frame.

Stake holding and positioning means.

5 Stake manipulating and controlling means.

Filler strand inserting means.

Filler strand packing mechanism, and

Driving mechanism.

10 In order to facilitate and simplify the description of the various parts and the operation of the machine I will describe said parts generally in the order above outlined.

15 *The frame.*

The frame comprises a base portion 1, a filler strand packing mechanism guide portion 2, and fabric limiting portion 3. The base portion includes a bottom base flange 4, 20 an upstanding annular flange 5 and a horizontal top wall 6, there being a centrally disposed tubular sleeve 6^b depending from said top wall and connecting it with a second horizontal wall 6^b near the flange 4. The filler strand packing mechanism guide portion 2 is made up of two horizontally disposed circular plates 7 and 8, respectively, which are rigidly connected together in vertically spaced apart relation by means of a set or plurality of upright rods 9—9. The top plate 8 is of a diameter greater than that of the bottom plate 7 and depending from the marginal part of said top plate is a second set or plurality of upright rods 10—10, to the bottom ends of which is fixed a ring 11 in the plane of the plate 7. The rods 9 and 10 are positioned on radial lines and are secured at their top and bottom ends to said plates and ring, as for example by the nuts 12 and 13 which permits of a more ready assembly of the parts. The rods 9 and 10 form guides for the sliding parts of the filler strand packing means. In Fig. 2 only the two diametrically opposite sets of rods 9 and 10 are shown, the other sets of rods which would be seen in this view being purposely omitted for the sake of clearness and simplicity.

50 The fabric limiting portion of the frame is composed of a ring 14 mounted on the top plate 8, just inside the annular row of rods 9 and is properly positioned thereon in a manner permitting its ready removal and replacement by dowel pins 15. Secured in said ring 14 and upstanding therefrom is a plurality of members 16 as best shown in Figs. 1, 2 and 5. In Fig. 2 only the two oppositely disposed members are shown, the others being omitted for sake of clearness. There is one of said members 16 for every stake in 55 the reed fabric and the purpose thereof will more fully appear later. The members 16 are given the shape desired in the finished fabric and act to limit the inward forming tendency of the fabric. The top end portions of said members are fixed in position

in the peripheral marginal part of a plate 17, which construction rigidly holds all of said members 16 in proper spaced relation.

55 *Stake holding and positioning means.*

The stake holding and positioning means comprises in part a ring or annular edgewise disposed band 20 in which are provided a plurality of spaced holes to receive the bottom ends of the stakes 21 which fit snugly 75 therein. As said band is of the kind employed in the machine of my prior patent before mentioned it is not thought necessary to more fully illustrate or describe the same in detail herein. The said ring or annular band 80 with the stakes 21 positioned thereon may be placed upon the member 14 where it will snugly surround or embrace the bottom ends of the fabric limiting members 16. When thus positioned, the stakes 21 upstand from 85 said band and will follow closely the general formation of the members 16. Having thus generally described the stake positioning and holding means together with the fabric limiting means I will next describe the means by 90 which the said stakes are manipulated to form the shed in which the filler strand is laid in single courses and in groups of courses upon desired stakes and the means by which said manipulation means is automatically 95 actuated and controlled.

55 *Stake manipulating and controlling means.*

The stake manipulating and controlling means includes a circular plate 22 of a size 100 substantially coextensive with the outer portions of the top ends of the members 16, and in one sense forming a continuation thereof. Said plate is removably mounted and positioned upon the plate 17 before mentioned 105 as by means of the dowel pins 23 (see Fig. 2) so that when they are operatively engaged they will rotate together. In the periphery of said plate 22 is provided a concave groove 24 in which a portion of a helical coiled 110 spring 25 is seated. Said spring is of such a size relative to said plate 22 that it tends to compress itself upon the plate and into said groove 24, said spring being formed with two complete convolutions for every 115 stake 21 of the fabric. This spring is so positioned with respect to the stakes that each stake can be moved into contiguous V-shaped spaces formed by oppositely disposed portions of the spring as is best shown in Fig. 120 9. The stakes may move into the associated V-shaped space a certain distance but cannot move out of the spring entirely and said spring acts to carry the stakes in proper spaced relation during that interval in which 125 they are separated or removed from the plate 22 for the insertion of the filler strand. The plate 22 is provided in its periphery with a plurality of arcuately spaced, vertical recesses 130 or pockets 26 for the accommodation of the

top end parts of the stakes, said pockets permitting the stakes to lie slightly within the outermost peripheral edge of said plate. The stakes 21 are of such length that their top or free ends which project above said plate are held in the proper spaced relation and prevented from leaving their associated recesses. In order to provide a safeguard to prevent said stakes from springing out of their respective recesses 26 for any reason whatsoever, I provide a second but smaller coiled spring 25^a which encircles the stakes 21 just below the helical stake guiding spring 25.

Upon the top of the plate 22 is fixed a duplex gear ring comprising top and bottom external gear members 27 and 28, respectively. Preferably the bottom gear member 28 is positioned between the top gear member and plate 22 and lag screws 29 pass through the top gear member and are threaded into said plate. The gear ring 28 while held in position by the gear ring 27 may be driven in a direction opposite that of the gear 27 when necessary, as will later appear. Within said duplex gear ring is a non-rotative circular plate 30, said plate and gear member 27 having coacting flange and groove construction by means of which said plate assists the members 16 in supporting the plate 22. The plate 30 is keyed to the top end of a centrally disposed, shaft 30^a which extends down through the plates 22, 17, 8 and 7, respectively, to have its bottom end non-rotatively secured in the sleeve 6^a before mentioned, the plates 7 and 8 having suitable bearing sleeves 7' and 8', respectively, journaled upon said shaft. Anchored at their bottom ends in said plate 30 are two diametrically opposite upright posts or standards 31—31 and disposed in planes at a right angle to the plane of said posts are laterally extending blocks 32—32, one of which is shown in perspective in Fig. 4. Each block is secured in position upon the plate 30 by means of bolts 33 which extend through the tapered sides as shown in Fig. 3. The outer end of each block 32 has extending side portions 35 which are thicker than the inner ends of said plate and the bottom surface of said thickened end and side parts are rounded upwardly in opposite directions from the middle thereof, as best shown in Fig. 8. To said bottom surface is secured coacting wear plates 36—37 which are spaced apart at the middle of the block in line with a groove 38 in the bottom portion of the block 32 at the middle thereof. Each bottom wear plate 37 has a shallow groove 37^a (see Fig. 7) in its top surface, and said bottom wear plates, together with the top wear plates define a shallow channel 39 which intercepts the groove 38 in said block in the plane of the gear ring 28. In said groove 38 is provided a flat, radially extending bar 38^a which is adjustably secured at its inner end to the plate 30 by means of bolts 38^b passing through short lon-

gitudinal slots 38^c in said bar and threading into said plate, enlarged openings 34 in the block 32 providing access to said bolts for the purpose of tightening or loosening them. The purpose of this channel 39 is to receive and guide a flexible metallic ribbon or tape 40 which is provided along one margin with teeth 41 meshing with the gear ring 28 and along its other margin with a plurality of humps and intermediate depressions 42 and 43, which operate to control the action of the stake manipulating means in a manner hereinafter to appear.

In the top surface of each block is provided a groove 44 which extends radially with respect to the centrally disposed non-rotative shaft 30^a. Said groove is adapted to receive a rib 45 on the underside of the base 46 of an upright standard 47. A bolt 46^b extends through a slot 46^a in said standard base 46 (see Fig. 1) and is threaded into the block 32 in a manner permitting a radially inward or outward adjustment of said standard upon said block 32.

To the outer end of the bar 38^a associated with each block 32 is fixed a depending guide member 48. In said guide member is formed a rectangular slot 49 extending parallel with and in the median plane of said recess. To one side of said slot, said guide member has outwardly extending top and bottom ears 50. Pivoted between said ears by means of a pin 51, is one end of a lever 52 which extends toward and terminates at its other end in substantially the vertical plane of the groove 44 in the block 32. A coiled spring 52^a surrounds said pivoted end of the lever and is attached at one end to one of the ears 50 and at its other end to said lever in such a manner as to normally urge the free end of said lever inwardly toward the associated block 32. To the free end of said lever is pivoted a trigger or latch 53 which, under the outward swinging movement of the lever, is adapted to engage the projecting top end of the desired stakes 21. Said trigger is pivoted to said free end of the lever 52 so as to be capable of a limited swinging movement, a spring 53^a being interposed between said lever and trigger for yieldingly holding it in a predetermined position with respect to said lever. In the slot 49 of the guide member 48 is slidably mounted a pusher bar 54 of rectangular cross section which is arranged in the plane of the tape or ribbon 40 where it passes through the recess 38 in the block 32. The inner end of said pusher bar is bifurcated to embrace opposite sides of the notch and recessed margin of said ribbon or tape, and carried by said end of said pusher bar is a roller 55 adapted to ride the various humps and depressions 42 and 43, respectively, and thus impart a corresponding in and out reciprocation to said pusher bar. The outer end of said pusher bar engages against a

roller 52^b carried by the lever 52, as best shown in Fig. 9, the spring 52^a acting to hold said lever in engagement with said pusher bar. It is apparent that as the gear ring 28 is rotated, the ribbon or tape will move through the channel 39 at the same rate of movement and that as each time a hump or projection of the tape or ribbon engages the roller 55 of the pusher bar a reciprocation is imparted thereto which, through the lever 52, causes the latch or trigger 53 to engage the desired stake and flex or stagger it outwardly. Thus by positioning the humps or projections on the tape in the desired manner any one stake or any one group of stakes may be staggered to provide the shed for the passage of the filler strand weaving means. To prevent the lever 52 from swinging outwardly too far, under the action of the pusher rod, I provide on the top of said lever a pin 52^c which is adapted to engage a stop shoulder 56 secured to the block 32 and overhanging said lever.

The controlling ribbons or tapes are wound upon and unwound from reels which are adapted to be positively driven so that, although said ribbons or tapes mesh with the lower gear of the duplex gear ring before mentioned, they do not rely upon this engagement alone for their movement. To this end I provide the following construction:— Fixed to the two upright posts 31—31 before mentioned are brackets 60—60, each of which includes a horizontally arranged yoke 61—61. Said yokes face in opposite directions and are disposed in a plane extending at a right angle to that of the blocks 32 and supported thereupon is a rectangular open frame-like plate 63 which connects said yokes together. The outer ends of said yokes terminate in horizontally spaced bearing sleeves 65—65 in which are journaled shafts 66 and 67, the ends of which project a suitable distance beyond said bearing sleeves 65. Loosely mounted on the ends of the shaft 66 are reels 68 and 68^a, and loosely mounted on the ends of the shaft 67 are similar reels 69 and 69^a, respectively. The ends of said shafts beyond the reels 68, 69 are each provided with a pulley 70 and 71, respectively, over which a belt (not shown) is trained to operatively connect them together. On the inner face of each reel is secured a clutch member 72—73—74 and 75, respectively. Keyed to the shafts 66—67 between the yoke sleeves 65 and the clutch members before mentioned, are associated clutch collars 72^a—73^a—74^a and 75^a, respectively. The clutch members 72^a—73^a are connected together by a U-shaped member 76 and the clutch members 74^a—75^a are also connected together by a similar U-shaped member 77. The adjacent end members 78 of said U-shaped members are slotted as at 79 and through said slots extend screws 80 which are threaded into the

open frame plate 63 near its middle. The ends of said U-shaped members connected to said associated clutch collars are further connected by arched brace bars 76^a—77^a, respectively. Journalled at its top end in said plate 63 between the members 78 is a manually operable shaft 81, the bottom end of which is journalled in a bracket 82 clamped to one of the posts 31. To said shaft, which is axially aligned with the shaft 30^a and preferably below the bracket 82 is fixed a handle 83 by means of which said shaft 81 may be turned. To the top end of said shaft 81 above the plate 63 is fixed a lever 84 with oppositely disposed slotted arms which overhang and are operatively connected to the members 78 of said U-shaped members, as best shown in Fig. 11.

Fixed to the shaft 67 between the bearings 65—65 is a pulley 85 which is driven by a belt 83 from a smaller pulley 87 secured to a short horizontal shaft 88 journalled in bearing sleeves 88' upstanding from a rectangular bracket plate 89 bolted to the plate 30 before mentioned. This plate 89 includes an upright bearing sleeve 90 which overhangs the gear rings 27—28 and in which is journalled a short vertical shaft 91 to the top end of which is fixed a bevel pinion 92. Said pinion meshes with a bevel gear 93 on the horizontal shaft 88. To the bottom end of said upright shaft 91 is fixed a gear pinion 94 which meshes with the top gear ring 27. Thus as said gear ring rotates it will, through the gearing and belt above mentioned drive the shaft 67 which, in turn, drives the shaft 66. With the clutch collars 73^a and 74^a engaged with their associated clutch members on the reels 68^a and 69, said reels will act to wind up the tapes 40—40 which pass through the associated guide channels 39—39 of the blocks 32 after unwinding from the reels 68 and 69^a, respectively. Said tapes are of such length that when the fabric is completed, the ends of said tapes on the unwinding or paying off reels are approached. However, it is not necessary in starting a new fabric to rewind the tape upon the depleted reel but all that is necessary is to actuate the handle 83 to shift the clutch members 72^a and 75^a into engagement with the clutch members 72—75 on the respective reels 68 and 69^a when said reels become the winding reels and the other reels become the unwinding or pay off reels. This shifting of the clutches is performed once at the completion of each woven fabric. As the tape is wound and unwound from the associated reels 68—69 and 68^a—69^a from the same side thereof as best shown in Fig. 1, it is advisable to provide a guide for the tape, being unwound or paid off from the reels 68 and 69^a so that said tapes need not turn such a sharp corner when entering or leaving the associated channels 39 in the blocks 32 as will tend to make said tapes bind

or buckle. To this end I provide the curved guide member 95 which, as best shown in Fig. 1 is secured to the top of the associated block 32, and terminates adjacent the reel 69^a. Of course, there is one of these guide members provided for each pair of associated reels.

Filler strand inserting means.—Mounted on each upright standard 47 is a bracket 98 secured thereto for both a vertical and horizontally swinging adjustment by means of a clamp screw 99. Said bracket extends laterally from said post and adjustably secured in the outer end thereof by means of a clamp screw 100 is a vertically arranged tubular stem 101. Said stem and bracket have tongue and groove connections by means of which angular turning movement between the two is prevented. Said tube is adapted to receive the filler strand 102 which passes out through its bottom end to be laid in the shed provided by the ends of the stakes which are staggered in the manner before mentioned. Said filler strand before it enters said stem passes over guide rollers 103 and 104 mounted, respectively on the bracket 98 and on a second bracket 98^a (see Fig. 1) also adjustably secured to said standard 47. The filler strands are carried upon supply reels (not shown) and pass up through a guide 105 mounted on a cross arm 106 which connects the two posts 31 together, as shown in Fig. 1 after which said strands pass over suitable tension devices 107 carried on the top end of one of said standards 31. From said tension device 33 the filler strands pass about the guide rolls 103—104 and to the respective stems 101, as before mentioned. The bottom end of each stem carries a tapered or pointed stake spreader comprising upper and lower members 108 and 109 respectively. As the staggered stakes approach said spreaded members they are caused to move further outwardly by engagement therewith to make a wider shed in which the filler strand which emanates from the bottom of the member 101 is laid. In this way, the filler strand is laid over one stake and under another and in some instances is laid in groups of courses over and under one or more stakes depending upon the operation of the stake staggering means as controlled by the tape or ribbon 40.

Filler strand packing means.—It is, of course, important that the filler strand be uniformly packed in place so that the finished fabric be of a character suitable for use upon high class articles. To this end I employ substantially the same "packing means" as is embodied in the machine of my prior patent hereinbefore referred to so that I have not illustrated the same in detail herein nor will the same be described in detail but only in general. It will be understood that where the filler strand is laid between the stakes at the upper portions thereof it is necessary to pack the same from a point adjacent its en-

trance in the shed between the stakes to a point contiguous the preformed fabric. As will be apparent, as the fabric is formed the extent of the packing varies. Said packing means includes a weight member 110 which is mounted for vertical sliding guiding movement between adjacent pairs of rods 9 and 10, by means of top and bottom stud shafts 111 and 112, the bottom one of which carries anti-friction rollers. In the bottom end of the weight member is provided a roller 113 which rolls upon a cam track member 114 supported by means of rods 115 from the top member 6 of the base. Said cam is of such formation as to impart the desired rise and fall to each weight at predetermined intervals as set forth in said prior patent, to elevate said weight and to permit the descent thereof once for every filler strand inserted. Said weight members are each provided near their bottom end with a radial shaft 116, the outer end of which may be manipulated by hand when desired, either to test the packer, to permit release of the fabric or for such other purpose as may be necessary. To the inner end of said shaft is pivotally connected the bottom end of an upstanding packer arm 117. Upon the top end of the packer arm 117, each of which extends up through an associated slot in the plate 8, is mounted a finger 118 having a nose portion 118^a which normally projects through the spaces between the fabric limiting members 16, as shown in Figs. 1 and 2. Said packing arm is urged radially outward by means of a tension spring 119 as shown in Fig. 2. The construction just described permits the packer arm and finger to follow the members 16 of different forms as is necessary for the construction of differently shaped fabrics. The cam track 114 which elevates the packer weights and arms is stationary with respect to the frame portions 2 and 3 which are rotated by means now to be described under the heading "Driving mechanism."

The machine is driven from a main drive shaft 120 suitably journaled in the base 1 as shown in Fig. 2. Upon the outer end thereof are fixed and loose pulleys 121 and 122 and secured upon the inner end thereof within the base is a bevel pinion 123. Said pinion meshes with a bevel gear 124 carried by a suitably journaled upright shaft 125. Upon the top end of said shaft is fixed a spur pinion 126 which meshes with a spur gear 127 secured to the under side of the plate 7. In this manner, the frame parts 2 and 3 are given a rotative movement and the plate 22 together with the gear member 27 is driven in a direction toward the pointed ends of the spreaders 108—109, as indicated by the arrow in Fig. 9.

Secured to the non-rotative or stationary plate 30 at a point substantially diametrically opposite the bracket 89 are two bearing 130

brackets 130 and 131, respectively, the latter including an upright tubular extension 132 (see Fig. 13) which is spaced a suitable distance above the plate 30. In the outer end 5 of the bracket 130 is fixed a bushing 134 in which is journalled the intermediate portion of a short upright shaft 135. To the bottom end of this shaft is fixed a pinion 136 which normally meshes with the bottom ring gear 28 10 and to the top end of said shaft is fixed a larger pinion 137. In the tubular extension 132 is a vertically movable or adjustable but non-rotative shaft 138 to the bottom end of which is keyed a vertically elongated pinion 139 and between said pinion and said sleeve is 15 a second gear 140 which is adapted to be moved into and out of meshing engagement with the gear 137. Said gears are so proportioned that when the gear members 139 and 20 140 are in their uppermost position the gear 139 will mesh with the ring gear 27 and the gear 140 will mesh with the gear 137 and when said gears 139 and 140 are in their lowermost position, the gear 139 will mesh with both ring 25 gears 27—28 and the gear 140 will be out of mesh with the gear 137. When the gears 139 and 140 are in the full line position shown in Fig. 13 the bottom ring gear 28 is driven in a direction opposite from that of the top ring 30 gear and when said gears 139 and 140 are in the dotted line position, the ring gear 28 is driven in the same direction as that of said ring gear 27.

Means are provided for manually raising 35 and lowering said gears 139 and 140 to change the rotation of the bottom ring gear each time a new fabric is started so that the desired tape reels 68—68^a and 69—69^a, respectively, are driven in the proper directions after the 40 associated clutches have been manipulated as before mentioned. Such means are as follows:—In the top end of the shaft 138 is provided a recess 142 in which two interiorly threaded half sleeves 143 are non-rotatively held by means of the pins 144, as shown in 45 Fig. 14. The bottom end of a correspondingly threaded rod 145 has threaded engagement with said sleeve parts but said rod is secured against endwise movement in a manner 50 soon to appear so that when said rod is turned in one direction the shaft 138 will move vertically downward and when said rod is turned in the other direction said shaft will move vertically upward, the gears 139 and 140 moving 55 in accordance therewith. The top end of the rod 145 is formed to provide a gear pinion 146 of a diameter larger than said rod. Said rod beyond the top end of said gear is journalled in the free end of a bracket 147 which is 60 secured to and extends laterally from one of the standards 47. A clip 148 secured to said bracket and engaging the bottom of the gear 146 provides the other bearing for said rod. Said gear meshes with a larger gear 149 which 65 is made rigid with a handle 150 journalled to

the underside of said bracket 147 near its free end. It is apparent that turning the handle 150 in the proper directions, will act through the threaded rod to shift the gear elements 139 and 140 into and out of the operative positions before mentioned. 70

It is apparent that the machine weaves upon diametrically opposite sides and that therefore the several duplicate parts bear the same reference numerals. In this manner, 75 the time consumed in weaving a complete fabric is materially reduced and the designs embodied therein are located diametrically opposite upon the finished article.

As the frame parts 2 and 3 are rotated in 80 one direction the stakes are staggered in accordance with the humps and depressions upon the tape so that the filler strand is laid in the shed, under one or more adjacent stakes and over others as is apparent to produce the 85 various designs which may be determined during the making of the tapes or ribbons 40. When one fabric is completed it is not necessary to rewind the tapes upon the reel from which they were just unwound, but all that 90 is necessary is to actuate the handle 83 to shift the reel clutches and then actuate the handle 150 to change the position of the gears 139 and 140 when the said tapes will operate in the opposite direction. After one fabric is completed the top part of the machine from the 95 plate 22 upward is removed, after which the fabric which is tubular in plan may be removed by lifting it upwardly above the plate 17. A new band 20 with the stakes 21 is 100 placed in position and the plate 22 and parts mounted thereon is replaced, after which the top ends of the stakes are positioned in the recesses 26 and under the springs 25—25^a. The filler strand may then be threaded over 105 and under the stakes either by hand or by simply pulling a sufficient length of filler from the supply reel because when the machine is started the filler strand is automatically laid in position and carried by the packers from the entrance position into a position closely adjacent the band 20. Continued rotation of the machine quickly lays 110 in a sufficient amount of strands to form the fabric to the proper height. The machine is then stopped, the incoming filler strands severed, the plate 22 and associated mechanism raised. The packer fingers which rest 115 upon the completed fabric, are then pressed inwardly by hand, thus lowering the associated weight so that it will rest upon the cam track. When all the fingers are thus released, the fabric can be bodily raised and removed 120 from the machine, the band removed from the stakes, new stakes then inserted therein, after which the band and new stakes thereon are replaced in position as before described. The plate 22 is again placed in position and 125 the machine is again ready to start weaving the next fabric. 130

Inasmuch as the disclosure heretofore set forth will readily suggest to others, modified structures whereby the substantial objects and advantages of my invention may be attained, I do not wish to be limited to the specific construction herein shown and described except as may be necessary by limitations in the hereunto appended claims.

I claim as my invention:

1. An apparatus for weaving a stake and strand fabric embodying therein, means adapted to engage desired stakes to move them out of their normal plane, and an end-wise movable member having one of its edges so formed as to operatively engage said means for actuating the same to move said desired stakes.

2. An apparatus for weaving a stake and strand fabric embodying therein, means adapted to engage desired stakes to move them out of their normal plane, and a movable tape having an edge surface of irregular contour to engage said stake engaging means for actuating the same in accordance with the contour of said surface.

3. An apparatus for weaving a stake and strand fabric embodying therein, means adapted to engage desired stakes to move them out of their normal plane, and an end-wise movable member of substantially great length having an edge surface so formed as to engage said stake engaging means for actuating the same in accordance with the contour of said edge.

4. An apparatus for weaving a stake and strand fabric embodying therein, means adapted to engage desired stakes to move them out of their normal plane, and a tape having an edge formed to provide humps and depression operatively engaged with said means to actuate the same in accordance with the arrangement of said hump and depressions.

5. An apparatus for weaving a stake and strand fabric embodying therein, means adapted to engage desired stakes to move them out of their normal plane and including a reciprocable plunger, a member having an edge formation engaging said plunger to actuate said stake engaging means, and means for imparting movement to said member.

6. An apparatus for weaving a stake and strand fabric embodying therein, means adapted to engage desired stakes to move them out of their normal plane, a tape like member having one edge formed to provide teeth and its other edge formed to provide humps and depressions for actuating said stake engaging means, and means meshing with said tape for moving the same in either direction.

7. An apparatus for weaving a stake and strand fabric embodying therein, means for laying a filler strand, means for manipulat-

ing the stakes to dispose desired stakes upon opposite sides of the plane in which said filler strand is laid, and a tape having an edge of irregular formation engaging said stake manipulating means for actuating the same to position a particular stake upon one side of said plane, so that a plurality of successive courses of filler strands is disposed upon the same side of said particular stake.

8. An apparatus for weaving a stake and strand fabric embodying therein, means for laying a filler strand, means for manipulating the stakes to dispose desired stakes upon opposite sides of the plane in which said filler strand is laid, and a tape having an edge of an irregular formation engaging said stake manipulating means for actuating the same to position a particular stake upon one side of said plane, so that a plurality of successive courses of filler strands is disposed upon the same side of said particular stake, and to position said particular stake upon the other side of said plane so that a second plurality of successive courses of filler strands is disposed upon the other side of said particular stake.

9. An apparatus for weaving a stake and strand fabric embodying therein, means for holding a plurality of stakes, means arranged to one side of said stake holding means for laying a filler strand, means for staggering desired stakes to dispose the same upon the other side of said plane, and a moving tape having an edge of irregular formation for engaging and automatically actuating said staggering means to position a particular stake upon one side of said plane so that a plurality of successive courses of filler strand is disposed upon the same side of said particular stake.

10. An apparatus for weaving a stake and strand fabric embodying therein, means for holding a plurality of stakes, means arranged to one side of said stake holding means for laying a filler strand, means for staggering desired stakes to dispose the same upon the other side of said plane, and a moving tape, having an edge of irregular formation for engaging and automatically actuating said staggering means to position a particular stake upon one side of said plane so that a plurality of successive courses of filler strand is disposed upon the same side of said particular stake, and to then position said particular stake upon the other side of said plane so that a second plurality of courses of filler strands is disposed upon the other side of said particular stake.

11. An apparatus for weaving a stake and strand fabric embodying therein, means for interweaving a strand upon said stakes, means having an edge of irregular formation for engaging and staggering said stakes, and a moving tape for automatically actuating said staggering means to so position said stakes

125

130

that said filler strand is laid in individual courses over and under opposite sides of desired stakes and in groups of courses over and under opposite sides of desired stakes.

- 5 12. An apparatus for weaving a stake and strand fabric embodying therein, means for holding a plurality of stakes, means for staggering desired stakes, means for interweaving a filler strand over and under said stakes, and a 10 moving tape having an edge of irregular formation for engaging and automatically actuating said staggering means to remove certain stakes out of said holding means and to one side of said filler strand interweaving means 15 so that said filler strand is laid in individual courses over and under opposite sides of desired stakes and in groups of courses over and under opposite sides of desired stakes.
13. An apparatus for weaving a stake and 20 strand fabric embodying therein, means for laying a filler strand, means for manipulating the stakes to dispose desired stakes upon opposite sides of the plane in which said filler strand is laid, a moving tape having an edge 25 of irregular formation for engaging and automatically actuating said stake manipulating means to position a particular stake upon one side of said plane so that a plurality of successive courses of filler strands is disposed 30 upon the same side of said particular stake, and means for imparting a movement to said tape.

14. An apparatus for weaving a stake and strand fabric embodying therein, means for 35 laying a filler strand, means for manipulating the stakes to dispose desired stakes upon opposite sides of the plane in which said filler strand is laid, a moving tape having an edge of irregular formation for engaging and automatically actuating said stake manipulating 40 means to position a particular stake upon one side of said plane so that a plurality of successive courses of filler strands is disposed upon the same side of said particular stake, 45 reels upon and from which said tapes are wound and unwound, and means for actuating said reels.

15. An apparatus for weaving a stake and strand fabric embodying therein, means for 50 laying a filler strand, means for manipulating the stakes to dispose desired stakes upon opposite sides of the plane in which said filler strand is laid, a moving tape having an edge of irregular formation for engaging and automatically actuating said stake manipulating 55 means to position a particular stake upon one side of said plane so that a plurality of successive courses of filler strands is disposed upon the same side of said particular stake, reels upon and from which said tapes 60 are wound and unwound, means for driving said winding reel and means for reversing the action of said reels.

16. An apparatus for weaving a stake and strand fabric embodying therein, a plurality 65

of means for laying filler strands, a device associated with each filler strand laying means for manipulating the stakes to dispose desired stakes upon opposite sides of the plane in which said filler strands are laid, and means 70 including tapes with irregular edges thereon acting in unison for automatically actuating said devices to position particular stakes upon one side of said plane, so that a plurality of successive courses of filler strands are disposed upon the same side of said particular stakes.

17. An apparatus for weaving a stake and strand fabric embodying therein, a plurality of means for laying filler strands, a device 80 associated with each filler strand laying means for manipulating the stakes to dispose desired stakes upon opposite sides of the plane in which said filler strands are laid, and means including tapes with irregular edges thereon 85 acting in unison for automatically actuating said devices to position particular stakes upon one side of said plane, so that a plurality of successive courses of filler strands are disposed upon the same side of said particular stakes, and to then position said particular stakes upon the other side of said plane so that a second plurality of successive courses 90 of filler strands are disposed upon the other side of said particular stakes.

18. An apparatus for weaving a stake and strand fabric embodying therein, a plurality of means for laying filler strands, a device 100 associated with each filler strand laying means for manipulating the stakes to dispose desired stakes upon opposite sides of the plane in which said filler strands are laid, and a plurality of moving tapes having irregular edges acting in unison and one associated 105 with each stake manipulating device for automatically actuating said devices to position particular stakes upon one side of said plane, so that a plurality of successive courses of filler strands is disposed upon the same side of said particular stakes.

19. An apparatus for weaving a stake and strand fabric embodying therein, a plurality of means for laying filler strands, a device 110 associated with each filler strand laying means for manipulating the stakes to dispose desired stakes upon opposite sides of the plane in which said filler strands are laid, and a plurality of moving tapes having an irregular edge formation acting in unison 115 and one associated with each stake manipulating device for automatically actuating said devices to position particular stakes upon one side of said plane, so that a plurality of successive courses of filler strands is disposed upon the same side of said particular stakes, and to position said particular stakes upon the other side of said plane so that a second 120 plurality of successive courses of filler strands is disposed upon the other side of said particular stakes.

20. An apparatus for weaving a stake and strand fabric embodying therein, a plurality of means for laying filler strands, a device associated with each filler strand laying means for manipulating the stakes to dispose desired stakes upon opposite sides of the plane in which said filler strands are laid, a plurality of moving tapes having an irregular edge formation acting in unison and one associated with each stake manipulating device for automatically actuating said devices to position particular stakes upon one side of said plane, so that a plurality of successive courses of filler strands is disposed upon the same side of said particular stakes, a pair of reels for each tape upon and from which each tape is wound and unwound and means for driving one of said reels.
21. An apparatus for weaving a stake and strand fabric embodying therein, a rotative stake holding and limiting means, a non-rotative means for laying a filler strand, non-rotative means for manipulating the stakes to dispose desired stakes upon opposite sides of the plane in which said filler strand is laid in the rotative movement of said stake holding and limiting means, and movable tape for automatically actuating said stake manipulating means to position a particular stake upon the same side of said plane at each revolution of said stake holding and manipulating means so that a plurality of successive courses of filler strands is disposed upon the same side of said particular stake.
22. An apparatus for weaving a stake and strand fabric embodying therein, a rotative stake holding and limiting means, a non-rotative means for laying a filler strand, non-rotative means for manipulating the stakes to dispose desired stakes upon opposite sides of the plane in which said filler strand is laid in the rotative movement of said stake holding and limiting means, and movable tape for automatically actuating said stake manipulating means to position a particular stake upon the same side of said plane at each revolution of said stake holding and manipulating means so that a plurality of successive courses of filler strands is disposed upon the same side of said particular stake, and to then position said particular stake upon the other side of said plane so that a second plurality of successive courses of filler strands is disposed upon the other side of said particular stake.
23. An apparatus for weaving a stake and strand fabric embodying therein, a rotative stake holding and limiting means, a non-rotative means for laying a filler strand, non-rotative means for manipulating the stakes to dispose desired stakes upon opposite sides of the plane in which said filler strand is laid in the rotative movement of said stake holding and limiting means, and a movable tape having an irregular edge formation for automatically actuating said stake manipulating device to position a particular stake upon the same side of said plane at each revolution of said stake holding and manipulating means so that a plurality of courses of filler strands is disposed upon the same side of said particular stake, a pair of reels upon and from which each tape is wound and unwound, and means for driving one of said reels.
24. An apparatus for weaving a stake and strand fabric embodying therein, a stake holding and limiting means, means including a swinging lever adapted to engage the stakes for staggering them, one of said means being relatively rotative with respect to the other, and a moving tape with an edge formation for automatically actuating said swinging lever to stagger the desired stake.
25. An apparatus for weaving a stake and strand fabric embodying therein, a rotative stake holding and limiting means, a swinging lever, adapted to engage the stakes for staggering them, a support, and a tape movable through said support and having an edge formation for automatically actuating said swinging lever to stagger the desired stakes.
26. An apparatus for weaving a stake and strand fabric embodying therein, a rotative stake holding and limiting means, a swinging lever, adapted to engage the stakes for staggering them, a fixed support for said lever, a pusher bar slidable in said support and operatively engaged with said lever and a tape movable with respect to said support for automatically actuating said pusher bar in one direction.
27. An apparatus for weaving a stake and strand fabric embodying therein, a rotative stake holding and limiting means, a spring pressed swinging lever adapted to engage the stakes for staggering them but normally held out of engagement therewith, a fixed support for said lever, a pusher bar slidable in said support and operatively engaged with said lever, and a tape movable with respect to said support for automatically actuating said pusher bar in one direction to impart a swinging movement to said lever against the action of its associated spring.
28. An apparatus for weaving a stake and strand fabric embodying therein, a rotative stake holding and limiting means, a spring pressed swinging lever, a support therefor, a pivoted trigger carried by said lever to engage the stakes for staggering them, means for limiting the swinging movement of said lever outwardly toward said stakes, a pusher bar slidable in said support and a tape movable with respect to said support for automatically actuating said pusher bar in one direction to impart a swinging movement to said lever toward said stakes.
29. An apparatus for weaving a stake and strand fabric embodying therein, a rotative stake holding and limiting means, a swinging

lever adapted to engage the stakes for staggering them, a fixed support for said lever, a tape movable with respect to said support and having one edge provided with projections and recessions, and means riding said projections and recessions and operatively connected to said lever to actuate the same to stagger the desired stakes.

30. An apparatus for weaving a stake and strand fabric embodying therein, a rotative stake holding and limiting means, a swinging lever adapted to engage the stakes for staggering them, a fixed support for said lever, a tape movable with respect to said support and having one edge provided with projections and recessions, and a pusher bar slideable in said support, one end of said pusher bar being bifurcated to embrace opposite sides of said tape, the other end of said pusher bar engaging the lever and a roller carried by the first mentioned end of said pusher bar and riding said projections and recessions to impart a swinging movement to said lever in conformity with said recessions and depressions.

31. An apparatus for weaving a stake and strand fabric embodying a swinging lever for staggering desired stakes, a support, means providing a guide channel in said support, a tape movable through said channel, one edge of said tape having projections and recessions therein, and means operatively connected to said lever and engaging said projections and recesses therein to impart a swinging movement to said lever in conformity with said depressions and recessions.

32. An apparatus for weaving a stake and strand fabric embodying therein, a rotative stake holding and limiting means, and including a top plate, a gear element rotative therewith, a second gear element loose with respect to said first gear element, means for manipulating desired stakes, a support, a tape movable through said support for automatically controlling and actuating said stake manipulating means, said tape having teeth along one edge meshing with said second gear element, and means for operatively connecting said gear elements together so that said second gear element may rotate with said first gear element or be driven in a direction opposite thereto.

33. An apparatus for weaving a stake and strand fabric embodying therein, a rotative stake holding and limiting means, and including a top plate, a gear element rotative therewith, a second gear element loose with respect to said first gear element, means for manipulating desired stakes, a support, a tape movable through said support for automatically controlling and actuating said stake manipulating means, said tape having teeth along one edge meshing with said second gear element, and manually operable

gearing for connecting said gear elements together so that said second gear element may rotate with said first gear element or be driven in a direction opposite thereto.

34. An apparatus for weaving a stake and strand fabric embodying therein, a rotative stake holding and limiting means including a top plate, a gear element rotative with respect thereto, a second gear element loose with respect to said first gear element, means for manipulating desired stakes, a support, a tape movable through said support for automatically controlling and actuating said stake manipulating means, said tape being driven by said second mentioned gear element, a pair of reels from and upon which said tape is wound and unwound, and means operatively connecting one of said reels with the first mentioned gear element to drive the same.

35. An apparatus for weaving a stake and strand fabric embodying therein, a rotative stake holding and limiting means including a top plate, a gear element rotative with respect thereto, a second gear element loose with respect to said first gear element, two sets of means for manipulating desired stakes upon opposite sides of said holding and limiting means, a fixed support for each set, a tape movable through each support for automatically controlling and actuating the associated stake manipulating means, said tapes being operatively engaged with said second mentioned gear element, a pair of reels for each tape upon and from which they are wound and unwound, means operatively connecting said gear elements together so that said second gear element may rotate with or be driven in a direction opposite said first mentioned gear element, and means operatively driving said winding reels from said first mentioned gears.

36. An apparatus for weaving a stake and strand fabric embodying therein, a rotative stake holding and limiting means including a top plate, a gear element rotative with respect thereto, a second gear element loose with respect to said first gear element, two sets of means for manipulating desired stakes upon opposite sides of said holding and limiting means, a fixed support for each set, a tape movable through each support for automatically controlling and actuating the associated stake manipulating means, said tapes being operatively engaged with said second mentioned gear element, a pair of reels for each tape upon and from which they are wound and unwound, means operatively connecting said gear elements together so that said second gear element may rotate with or be driven in a direction opposite said first mentioned gear element, and means operatively driving said reels from said first mentioned gear element and including devices

by which said reels may be driven in opposite directions.

37. In combination with a machine for weaving a stake and strand fabric including two sets of means for engaging desired stakes to move them to one side of their normal plane, a tape for actuating each of said means, two parallel shafts, means providing bearings in which said shafts are journaled, a 10 pair of tape winding and unwinding reels each including a clutch member loosely mounted on each shaft, associated clutch members keyed to said shafts, means for operatively connecting said shafts together, 15 means for driving one of said shafts, and means for operating the associated clutch member to connect diagonally opposite reels to said shafts and to simultaneously disconnect the other diagonally opposite reels from 20 said shafts.

38. An actuating member for the stake manipulating means of a stake and strand loom of the circular type comprising a flexi-

ble metallic tape having teeth in one of its edges and having projections and recessions 25 in its other edge, said projections in some parts of the tape being equally spaced apart and in other parts of said tape being unequally spaced apart.

39. An apparatus for weaving a stake and strand fabric embodying therein, means adapted to engage desired stakes to move them out of their normal plane, a tape like member having one edge formed to provide teeth and its other edge formed to provide 35 humps and depressions for actuating said stake engaging means, means through which said tape has sliding guiding bearing and in which a portion of said stake engaging means is engaged and a gear meshing with 40 the teeth in said edge of the tape for imparting movement to the same.

In testimony whereof, I have hereunto set my hand, this 20th day of December, 1924.

MARSHALL B. LLOYD.
